UNITED STATES PATENT OFFICE.

GEORGE A. EYNON, OF CLEVELAND, OHIO, ASSIGNOR TO THE UNIVERSAL CARBURETOR COMPANY, OF CLEVELAND, OHIO, A CORPORATION OF OHIO.

METHOD OF GASIFYING LIQUIDS.

1,181,516.

Specification of Letters Patent.

Patented May 2, 1916.

Application filed October 25, 1915. Serial No. 57,737.

To all whom it may concern:

Be it known that I, GEORGE A. EYNON, a citizen of the United States, and a resident of Cleveland, county of Cuyahoga, and State of Ohio, have invented new and useful Improvements in Methods of Gasifying Liquids, of which the following is a specification, the principle of the invention being herein explained and the best mode in which I have contemplated applying that principle, so as to distinguish it from other inventions.

My invention relates to processes for gasifying liquids.

15 More particularly, my invention relates to processes for gasifying fuels for use in operating internal combustion engines.

As a particular illustration of my improved process, I shall describe hereinafter means in which said process may be successfully carried out to gasify petroleum, not only the lighter distillates but also the heavier distillates, especially all grades of kerosene or even crude oil; particularly a carburetor construction suitable for carrying out the gasifying of petroleum for use in automobiles and allied mechanism. These means, which I shall hereinafter describe, illustrating steps for the carrying out of my improved process, are those upon which my pending application for United States Letters Patent, Serial No. 855,894 (series of 1900) is based, and the improved process herein described and hereinafter claimed 30 has been divided out of said application, Serial No. 855,894 (series of 1900.)

By thus referring to the use of the present invention in connection with internal combustion engines, I do not mean to limit 40 the same to this use, as many other adaptations of the invention will readily suggest themselves to men skilled in the various arts.

To the accomplishment of the foregoing and related ends, said invention, then, consists of the steps herein fully described and particularly pointed out in the claims.

The annexed drawings and the following description set forth in detail means for and one mode of carrying out the invention, such disclosed mode of illustrating, however, but one of the various ways in which the principle of the invention may be used.

In said annexed drawings:—Figure 1 is a central vertical section of the means here-

in described, illustrating one mode of carrying out my improved process; Fig. 2 is an elevation of the same; Fig. 3 is a horizontal section upon the lines 3—3, Fig. 1; Fig. 4 is a vertical section and elevation upon the lines 4—4, Fig. 3; Fig. 5 is a broken vertical section upon the lines 5—5, Fig. 3, illustrating particularly the mixing and combustion chambers and the heating and ignition devices, hereinafter fully described; Fig. 6 is a broken perspective view of the choke-plates hereinafter fully described; and Fig. 7 is a vertical section upon the line 7—7, Fig. 1.

Referring to the annexed drawings, 1 represents a fuel supply pipe, 2 a screen or filter, 3 a float needle valve opening regulated by float needle valve 4 operated by float 5 and levers 6 by which a constant level of fuel is maintained in the fuel chamber.

Fuel passes through the passage 7 toward 75 the preliminary mixing chamber 8, the flow being regulated by the adjusting shaft 9 acting as a valve at 10, said shaft being provided with a threaded portion which causes it upon being turned to regulate the flow 80 of fuel at 10. This regulation is effected as follows: A lever 38 is secured to shaft 9 and a ratchet-wheel 39 is rotatably mounted upon the said shaft and is engaged by an opening connection 40 which is secured to the lever 38. An adjusting lever 37 is rotatably mounted upon the shaft 9, 85 is secured to ratchet wheel 39, and is hinged to a connecting link 36 which in turn is hinged to an adjusting lever 32 provided 90 with extended lugs 33. Lever 32 is actuated by the movement of the shaft 29 upon which is mounted a butterfly valve 28 of standard design for controlling the amount of gas given to the engine. Shaft 29 is operated by means of lever 30 and connecting rod 31. The limits of movement for opening and closing the valve 28 are fixed by the adjusting screw 34 and stop lug 35 against which the extended lugs 33 on the adjusting 95 lever 32 strike. Assuming then that the fuel controlled as desired is being fed into the preliminary mixing chamber 8, the apparatus is designed to intimately intermix the fuel and air within the spirit of the invention described and claimed in my pending application for United States Letters Patent Serial No. 794,266 (series of 1900) in

that a plurality of separated columns of intimately intermixed fuel and air are formed and then these separate columns are intermixed. This preliminary mixing and then the intermixing are accomplished as described in said pending application by means of an upper and a lower baffling plate 8¹ and 8² respectively provided with spaced apertures 12 and 13 through which the air from the primary air opening 11 passes. The openings 12 are larger than the openings 13 but said openings 12 and 13 correspond in number and position. The fuel passes from the passage 7 laterally into the preliminary mixing chamber 8 and is caught up while spread out in a thin body and intimately intermixed with the air in the air currents through the openings 13 and 12, thus forming a number of separate columns of mixed vapor and air. The lateral movement of the fuel and the size and position of the apertures 12 set up eddy currents in the separate columns thus preliminarily mixing the fuel and air. The preliminary mixing chamber 8 is smaller in diameter than the mixing and combustion chamber proper 17, the upper part of which will be hereinafter fully described as a combustion chamber, so that some air passes up around said preliminary mixing chamber 8. Upon emerging from the apertures 12, the separate columns of intimately mixed fuel and air intermix, the resulting product being an extremely intimate intermixture of the separate columns of liquid and air, the proportions of each being controlled by the relative sizes of the air and fuel supply conduits, as well as by the proportions of the apertures 12 and 13 in the plates 8¹ and 8² of the preliminary mixing chamber.

For the purposes of starting up the automobile engine, the intimately intermixed fuel and air is vaporized by means of a heating element 14 through which an electric current is passed which vaporizes the mixture absorbed by a wicking 15 about which the heating element shown as a coil 14 is wound. Said wicking is comprised of non-combustible and as far as possible non-destructible absorbent material and is placed above the preliminary mixing chamber 8, being held in place by the heating element 14 and further held in place by a metal collar 14¹ which is fastened to or can be made integrally with the upper plate 8¹ of the preliminary mixing chamber 8, said collar 14¹ being inside of the apertures 12 so that said wicking 15 lies in an idle or semi-idle spot. A very small part only of the mixture being drawn through is thus absorbed by the wicking 15 and heated by the heating element 14. A spark plug 16 is inserted over the wicking 15 and a spark is produced at the idle or semi-idle spot which starts into a flame the highly vaporized liq-

uid produced by the action of the heating element 14. The entire combustion chamber 17 is thus immediately filled with fire or flame and the vaporized liquid continuously drawn forward by the suction of the engine 70 passes through this flame.

In order that the aforementioned flame may not pass into the engine and in order that no more than a small per cent of the vaporized liquid may be burned or consumed 75 by the flame, choke plates 18 and 19 are provided, the former having annular rows of holes 20 and downwardly projecting tubes 21, and the latter a central hole 53 leading into the auxiliary air opening 54. The purpose of the tubes 21 is to spread the flame in the combustion chamber 17 and thus keep the latter full of flame. These plates 18 and 19 effectually check the flame and allow the highly gasified products of the incomplete 80 combustion to pass through to be mixed with the auxiliary air and then through the intake manifold to the engine cylinders. In order to make the action more positive and to sustain the supply of gas at all times, a 85 supplementary non-combustible, non-destructible wicking 22 is provided which is placed on top of the upper plate 8¹ of the preliminary mixing chamber 8 outside of the apertures 12 and adjacent to the outer 90 wall of said preliminary mixing chamber, being held in place by means of annular rings 22¹ formed integral with said chamber 8. The use of this auxiliary wicking 22 has not been found necessary under many conditions but with the use of certain fuels and under certain limited conditions has been found to assist the action. In order to better control and check the flame in the combustion chamber 17, a baffle plate 23 is 95 provided below the choke plate 18 of somewhat smaller diameter than the diameter of the combustion chamber which forces the flame outwardly thus assisting in the control of the same. Said baffle plate 23 is provided with an aperture 23¹, Fig. 5, located over the spark gap and which serves to promote a slight current of air movement past the spark point thus sustaining the fire or flame. An additional non-combustible, non-destructible wicking 24 is carried on top of the baffle plate 23 which further helps to sustain the flame and to make the action positive under all running conditions. Only 100 under certain limited conditions and with the use of certain heavy fuels is the use of this auxiliary wicking 24 been found necessary. In the event that the heating element 14 has failed for the purposes of starting the engine, I use the priming tube 26 connected 105 with the priming cup 27 into which latter may be poured a light fuel. I have never found it necessary to use the priming tube 26 and fill the priming cup 27 with a light fuel under any conditions, but the same are 110

provided in order that if at any time the heating element 14 fails to produce a gas with which the engine might be readily started, the difficulty might be overcome by the use of some gasoline or other light fuel in the priming cup 27. After the engine has been effectually started the use of the heating element 14 is discontinued. Only the early flow of the mixture is heated and vaporized by the heating element 14, the latter being turned off or positively rendered non-effective just so soon as a material part of the mixture, or the early flow thereof, has been subjected to all the steps of the process and has resulted in a highly gasified product which is being properly exploded in the engine and producing the desired working impulses.

The auxiliary air intake 54 is supplied through the valve 41 guided by pin 41¹ adjustably seated on 43 and locked thereon in any predetermined position by means of lock screw 44 and the latter is adjusted by cap 46 which is in turn held in any predetermined position by spring 45. A dust cup 47 is also provided. As the suction from the engine increases, the valve 41 opens and is held by spring 42. A supplementary air valve 48 is provided having openings 49 which is rotatably mounted on a pin 50 and is held by a spring 51. The air passes through the openings 49 thence through the openings 52 in the carbureter body and mingles with the gas drawn through opening 53 from the combustion chamber 17. The valve 48 is set and the openings 49 are constant.

The foregoing method has been found to secure a complete gasification not only of the light distillates of petroleum, but also of the heavy distillates such as all grades of alcohol, kerosene and crude oil. The satisfactory use of these heavier distillates effects a great economy in the cost of operation of internal combustion engines. The true gas that I thus obtain from the heavier distillates is obtained at ordinary atmospheric pressure and is a gas of a different quality than is produced by any process with which I have heretofore been acquainted in that for a long period it will not condense at ordinary atmospheric temperature, a gas which when further mixed with air is very highly explosive and which leaves little or no carbon or other deposit in the cylinders, and creates very little smoke at the exhaust. By the use of the heating step described, illustrated in the disclosed apparatus by the heating element 14, in combination with the preliminary mixing illustrated in the disclosed apparatus as effected in the preliminary mixing chamber 8, which step in itself intimately mixes the fuel and air, it is not necessary to use the light distillates for starting the engine to raise the

temperature of the working parts. The method has a very broad field of operation, in that gasoline and other light distillates may be gasified without the aid of the heating step; also without the aid of this step, my invention will more highly vaporize kerosene and the heavy distillates than any process with which I am acquainted; and with the aid of this step will convert these heavy distillates into a true gas highly satisfactory even for the starting of the engine. I desire to particularly point out that the combination of steps which I have described procures very positive action of the engine under all running conditions. Furthermore, I desire to point out that, inasmuch as it is not necessary to rely on the heat of the exhaust gases, my invention can be carried out in any type of internal combustion engine regardless of the position of the exhaust manifold.

The various uses to which my improved process can be applied will readily suggest themselves to those skilled in the various arts.

The invention has already been successfully applied to the gasification of kerosene in the use of the latter in internal combustion engines, and it is for this reason that the foregoing description has dealt with such an application of the invention as affording the best and clearest illustration of the steps of my improved method.

I claim:

1. In a method of gasifying liquids, the steps which consist, in producing an intimate intermixture of fuel and air by catching up the fuel, while spread out in a thin body, in a plurality of separated columns of air; intermixing said columns of fuel and air in the presence of more air; producing a flame fed by the resultant mixture; and smothering the same before a substantial amount of the mixture has been consumed.

2. In a method of gasifying liquids, the steps which consists, in producing an intermixture of fuel and air; heating such mixture by bringing it into contact with an absorbent material associated with a live electric coil and capable when saturated of holding a comparatively small amount of the mixture; then, gasifying the heated mixture by producing a flame fed by said heated mixture and smothering the same before a substantial amount of the mixture has been consumed.

3. In a method of continuous gasification of liquids for producing automobile motive power or analogous results, the steps which consist, in setting up and maintaining currents of fuel and air; heating the fuel in the early flow of said fuel current; intermingling the heated fuel with the air; and subjecting the heated mixture to incomplete combustion, the heating of further fuel be-

ing omitted after the early flow thereof has been subjected to the entire cycle of operations effecting gasification.

4. In a method of continuous gasification of liquids for producing automobile motive power or analogous results, the steps which consist, in setting up and maintaining currents of fuel and air; intimately intermixing the same; heating the early flow of said mixture by bringing it into contact with an absorbent material associated with a heating element and capable when saturated of holding a comparatively small amount of the mixture; and subjecting the heated mixture to incomplete combustion, said heating element being non-effective after the early flow of the intimately intermixed fuel and air have been subjected to the entire cycle of operations effecting gasification.
5. In a method of continuous gasification of liquids for producing automobile motive power or analogous results, the steps which

consist, in setting up and maintaining currents of fuel and air; intimately intermixing the same; heating the early flow of 25 said mixture by bringing it into contact with an absorbent material associated with a live electric coil and capable when saturated of holding a comparatively small amount of the mixture; subjecting the heated 30 mixture to the action of a spark plug and simultaneously mixing with more air; smothering the resultant flame; and mixing the resultant products with more air, said electric coil being positively rendered non- 35 effective after the early flow of the intimately intermixed fuel and air have been subjected to the entire cycle of operation effecting gasification.

Signed by me, this 18th day of Oct., 1915. 40
GEORGE A. EYNON.
